[57] CLAIM

The ornamental design for a shelf mounted storage basket, as shown and described.

DESCRIPTION

FIG. 1 is a front elevational view of a shelf mounted storage basket showing my new design;

FIG. 2 is right side elevational view, the left side being a mirror image thereof;

FIG. 3 is a top plan view thereof;

FIG. 4 is a rear elevational view thereof; and

FIG. 5 is a perspective view thereof.

Fig. 1
